UNITED STATES PATENT OFFICE.

EDWARD KIRBY BOTTLE, OF ELMIRA, NEW YORK, ASSIGNOR TO AMERICAN SALES BOOK COMPANY, LIMITED, OF TORONTO, CANADA, A CORPORATION OF CANADA.

SALES-BOOK.

1,068,215.

Specification of Letters Patent. Patented July 22, 1913.

Application filed November 16, 1911. Serial No. 660,561.

To all whom it may concern:

Be it known that I, EDWARD KIRBY BOTTLE, a citizen of the United States, residing at Elmira, in the county of Chemung and State of New York, have invented certain new and useful Improvements in Sales-Books, of which the following is a full, clear, and exact description, such as will enable others skilled in the art to which it appertains to make and use the same.

This invention relates to sales books.

One of the objects of this invention is to provide a simple and practical form of sales book particularly adapted to be used in stores.

Another object is to provide an inexpensive and self-contained sales book of the above character.

A further object is to provide a practical device adapted to hold a sales pad of any desired size and to permit of ready manipulation thereof.

Other objects will be in part obvious and in part pointed out hereinafter.

The invention accordingly consists in the features of construction, combinations of elements and arrangement of parts which will be exemplified in the construction hereinafter set forth, and the scope of the application of which will be indicated in the following claims.

In the accompanying drawing, wherein is shown one of the various possible embodiments of my invention, Figure 1 is a longitudinal sectional view of the complete device; and Fig. 2 is a plan view thereof.

Similar reference characters refer to similar parts throughout the several views of the drawing.

Referring now to the drawing in detail, there is shown at 1 the top of a table or counter provided with a hole 2 or recess therein, depending upon its thickness. Countersunk in this recess is a casing or receptacle 3 of a depth sufficient to hold a pad 4 of five hundred or a thousand leaves as desired. This pad is preferably made of a continuously folded web, and comprises a plurality of sets of original and duplicate leaves 5 and 6 respectively. The back of each original leaf 5 is carbonized, as indicated by the heavy line 7, throughout the greater part of its rear surface, or the area opposite the ruled lines receiving the record 55 of the transaction to be transferred to the

duplicate sheet 6. This pad 4 rests upon a movable bottom or follower plate 8 having a downwardly projecting peripheral flange 9 to prevent the plate from binding within the casing as it moves upwardly under the action of a flat spring 10. The spring 10 is secured at one end to the under side of the table by means of a screw 11, while its other end is provided with a slot 12 (Fig. 2) through which passes a screw 13 engaging a downwardly projecting stem 14 of the follower plate 8. The spring 10 is of sufficient strength to urge the pad upwardly when the upper set of leaves is removed therefrom. The pad is retained in the receptacle by means of a flat plate 15 hinged at 16 to one side of the casing. Associated with this hinge is a spring 17 relatively stronger than the spring 10 so as always to retain the leaves of the pad within the casing except when intentionally removed therefrom. The plate 15 not only forms a cover for the receptacle, which may be removed when inserting a new pad, but also provides a backing or support for the top set of leaves of a pad when being written upon. It will be noted that the cover 15 provides with the casing 3 a transverse opening 18 through which the leaves of the pad may be drawn. The casing is cut away at the point 19 to permit the operator to more easily raise the plate 15 or to insert his thumb and finger to grasp the edge of the top leaf and draw the same outwardly when desired. In operation, however, it may be more convenient to arrange the succeeding set of leaves upon the plate 15 for the next transaction before tearing off the top set upon which the last transaction has just been recorded. By having the casing countersunk in the surface of the table with the upper surface of the plate 15 below the level of the top of the table, the leaves of the pad may rest upon the plate 15 in the manner shown without danger of becoming mutilated if anything is placed on the table above the same.

The operation and method of using a device of this character is substantially as follows: This device, which may be applied to any counter or table by cutting a hole or recess therein, is first provided with a pad by swinging the cover 15 upwardly about its hinge 16, placing a pad upon the follower plate 8 and pressing downwardly thereon against the action of the spring 10 until the

cover when closed will lie below the upper surface of the table. The top set of leaves is then drawn out through the opening 18 by grasping the edge thereof through the cut away portion 19, as previously stated, until a complete set, that is, an original and duplicate leaf, are removed. These are folded back upon the plate 15, whereupon the device is ready for recording the first transaction. After recording the transaction the top set of leaves is drawn forwardly so as to pull out the second set of leaves which then are folded back upon themselves, after which the leaves upon which the first transaction has been recorded may be torn off. By placing the device relatively close to the edge of the table, as herein shown, the edge will form a convenient tearing line, although as each leaf is separated from the adjacent leaves by weakening lines, such as perforations, the leaves may be easily and quickly separated from each other and from the pad in any position. As the leaves of the pad are removed, the follower plate, under the action of the spring 10, will force the remaining sets upwardly, whereby they will always be within convenient reach of the operator.

The term "table" is broadly used in the following claims to denote any article of furniture having a firm supporting surface such as a desk, counter or the like.

It is thus seen that this invention provides a simple and practical device, accomplishing, among others, all of the objects and advantages above set forth.

As many changes could be made in the above construction and many apparently widely different embodiments of this invention could be made without departing from the scope thereof, it is intended that all matter contained in the above description or shown in the accompanying drawings shall be interpreted as illustrative and not in a limited sense.

Having described my invention, what I claim as new and desire to secure by Letters Patent is:

1. In a device of the character described, in combination, a table having a recess, a casing positioned in said recess, a cover for said casing, and a pad within said casing comprising a plurality of sets of original and duplicate leaves and manifolding means associated therewith, said pad and casing being arranged to permit the leaves to be withdrawn set by set from the casing and laid over said cover without detachment from the pad whereby duplicate copies of any transaction may be inscribed thereon without affecting the lower sets of leaves.

2. In a device of the character described, in combination, a table having an opening in the upper surface thereof, a casing positioned in said opening, a cover for said cas-

ing coacting therewith to form a slot along one edge of said cover, and a pad within said casing comprising a continuous web folded to form a plurality of sets of original and duplicate leaves adapted to be threaded through said slot set by set and laid over the cover when inscriptions are being made thereon.

3. In a device of the character described, in combination, a table having a recess therein, a cover for said recess, said parts being constructed to form an opening when the cover is in closed position through which the leaves of a pad may be drawn before being written upon, a pad of continuously folded leaves in said recess, and spring means urging said pad toward the cover of said recess.

4. In a device of the character described, in combination, a relatively fixed support having a recess therein, a casing mounted in said recess, a pad of original and duplicate leaves positioned within said casing, manifolding means associated with said pad, a resiliently held plate engaging the under side of said pad adapted to urge the pad upwardly, and means for retaining said pad in position.

5. In a device of the character described, in combination, a relatively fixed support having a recess therein, a casing mounted in said recess, a pad positioned within said casing, a resiliently held plate engaging the under side of said pad adapted to urge the pad upwardly, and a spring held plate hinged to said casing for holding said pad in proper position, said plate being adapted to serve as a back for the top set of leaves when being written upon.

6. In a device of the character described, in combination, a relatively fixed support having a recess therein, a casing mounted in said recess, a pad adapted to fit within said casing, a follower plate adapted to urge said pad upwardly, a cover for said receptacle, said device having an opening in the upper part through which the leaves of the pad may be drawn, and manifolding means connected with said device.

7. In a device of the character described, in combination, a relatively fixed support having a recess therein, a casing mounted in said recess, a pad adapted to fit within said casing, means adapted to urge said pad upwardly, a cover for said receptacle providing therewith an opening through which the leaves of the pad may be drawn, said cover being hinged to one side of said casing, and means for holding said cover in place.

8. In a device of the character described, in combination, a table having a recess in the upper surface thereof, a casing countersunk in said recess, a pad mounted within said casing, a movable spring pressed bottom to said casing adapted to urge the pad

upwardly, and a cover for said casing for retaining the pad in proper position, and forming with said casing an opening through which the leaves of the pad may be drawn, said cover acting as a support for the leaves of the pad when being written upon.

9. In a device of the character described, in combination, a table having a recess in the upper surface thereof, a casing countersunk in said recess, and a pad mounted within said casing, said pad comprising a plurality of sets of original and duplicate leaves, the back of each original leaf being carbonized.

10. In a device of the character described, in combination, a table, a casing countersunk in the surface of said table, a pad within said casing, said pad comprising a plurality of sets of original and duplicate leaves, the back of each original leaf being carbonized, and a means for holding said pad in position within said casing, said means acting as a support for the top set of leaves when being written upon.

11. In a device of the character described, in combination, a table, a casing countersunk in the surface thereof, a pad within said casing, and a cover therefor acting as a support for the leaves of the pad when being written upon, said cover being below the surface of the table.

12. In a device of the character described, in combination, a table, a casing countersunk in the surface thereof, a pad within said casing, and a cover therefor acting as a support for the leaves of the pad when being written upon, said cover being hinged to said casing to permit the insertion of a new pad and being below the surface of the table to prevent mutilation of the top leaves when resting upon said cover.

13. In a device of the character described, in combination, a table, a rectangular casing countersunk in the surface thereof, a movable bottom to said casing, spring pressed means tending to urge said bottom upwardly, a pad resting on said bottom within the casing, and a cover operatively connected with said casing for holding said pad in proper position and providing at one end an opening through which the leaves of the pad may be drawn, said leaves adapted to rest on said cover when being written upon.

14. In a device of the character described, in combination, a table, a rectangular casing countersunk in the surface thereof, a movable bottom to said casing, a spring pressed means tending to urge said bottom upwardly, and a pad resting on said bottom within the casing, said pad having a plurality of sets of original and duplicate leaves, the back of each original leaf being carbonized.

15. In a device of the character described, in combination, a table, a rectangular casing countersunk in the surface thereof, a movable bottom to said casing, a spring pressed means tending to urge said bottom upwardly, a pad resting on said bottom within the casing, said pad having a continuously folded web forming a plurality of sets of original and duplicate leaves, the back of each original leaf being carbonized, and a cover for said casing upon which the top set of leaves is adapted to rest when being written upon.

In testimony whereof I affix my signature, in the presence of two witnesses.

EDWARD KIRBY BOTTLE.
